US00D584686S

(12) **United States Design Patent**
Gudewer

(10) **Patent No.:** **US D584,686 S**
(45) **Date of Patent:** **** Jan. 13, 2009**

(54) **NACELLE OF A WIND TURBINE**

(75) Inventor: **Wilko Gudewer**, Norden (DE)

(73) Assignee: **Aloys Wobben**, Aurich (DE)

(**) Term: **14 Years**

(21) Appl. No.: **29/302,695**

(22) Filed: **Jan. 22, 2008**

(30) **Foreign Application Priority Data**

Jul. 23, 2007 (EM) 762 729

CLAIM

The ornamental design for a nacelle of a wind turbine, as shown and described.

DESCRIPTION

FIG. 1 is a front right perspective view of a nacelle of a wind turbine showing my new design;

FIG. 2 is a top plan view thereof;

FIG. 3 is a rear side view thereof;

FIG. 4 is a right side view thereof;

FIG. 5 is a left side view thereof;

FIG. 6 is a bottom plan view thereof; and,

FIG. 7 is a front view thereof.

The portions shown in broken lines in FIG. 1 represents unclaimed environment and forms no part of the claimed design.

1 Claim, 7 Drawing Sheets
